United States Patent [19]

Pushelberg et al.

[11] Patent Number: Des. 304,325

[45] Date of Patent: ** Oct. 31, 1989

[54] **ENCLOSURE FOR WIRES
INTERCONNECTING ELECTRONIC
EQUIPMENT MODULES**

[75] Inventors: **Floyd J. Pushelberg, Ottawa,
Canada; James A. Rintala, Livonia;
Leo B. Koziol, Canton, both of Mich.**

[73] Assignee: **Northern Telecom Limited, Montreal,
Canada**

[**] Term: **14 Years**

[21] Appl. No.: **805,103**

[22] Filed: **Nov. 13, 1985**

[52] U.S. Cl. **D13/40; D13/13**

[58] Field of Search **D13/24-31,
D13/11-13, 18-31, 40; 439/557; 361/331, 334,
357; 248/52; 220/241, 242; 174/67**

[57] **CLAIM**

The ornamental design for an enclosure for wires interconnecting electronic equipment modules, as shown and described.

DESCRIPTION

FIG. 1 is a perspective view of an enclosure for wires interconnecting electronic equipment modules showing our new design;

FIG. 2 is a left end elevational view thereof;

FIG. 3 is a right end elevational view thereof;

FIG. 4 is a front elevational view thereof;

FIG. 5 is a bottom plan view thereof;

FIG. 6 is a rear elevational view thereof;

FIG. 7 is a top plan view thereof.

FIG. 4

FIG. 5

FIG. 6

FIG. 7
